(57) **CLAIM**

The ornamental design for a bracket and pulley assembly, as shown and described.

DESCRIPTION

FIG. 1 is a front perspective view of a bracket and pulley assembly of my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front perspective view thereof in a different environment;

FIG. 9 is another front view thereof in a different environment;

FIG. 10 is another rear view thereof in a different environment;

FIG. 11 is another left side view thereof in a different environment;

FIG. 12 is another right side view thereof in a different environment;

FIG. 13 is another top view thereof in a different environment; and,

FIG. 14 is another bottom view thereof in a different environment.

Where included, broken lines showing environment or structure are for illustrative purposes only and form no part of the claimed design.

1 Claim, 12 Drawing Sheets
